UNITED STATES PATENT OFFICE.

HARVEY J. WARNER, OF TAKOMA PARK, DISTRICT OF COLUMBIA, ASSIGNOR TO THE
U. S. AVIATION AND AUTO CO., OF DENVER, COLORADO, A CORPORATION.

INTERNAL-COMBUSTION ENGINE.

1,263,972.

Specification of Letters Patent. Patented Apr. 23, 1918.

Application filed December 1, 1916. Serial No. 134,441.

To all whom it may concern:

Be it known that I, HARVEY J. WARNER, a citizen of the United States, residing at Takoma Park, in the District of Columbia, have invented certain new and useful Improvements in Internal-Combustion Engines; and I do declare the following to be a full, clear, and exact description of the invention, such as will enable others skilled in the art to which it appertains to make and use the same.

My invention relates more particularly to internal combustion engines of the rotating cylinder type designed primarily for use on aeroplanes and other air craft although the improved features of construction are not limited to this type of engine.

On account of the fact that the two-cycle engine is capable of creating a greater number of working strokes per revolution than the four-cycle, this engine should be by far the most efficient for high speed work but the two-cycle engines of the types now in use are not so constructed as to permit them to operate effectively when constructed with rotating rather than fixed cylinders. Furthermore, with the common type of two-cycle engine in which the incoming charge expels the exhaust gases, there is a great waste of power since the incoming mixture is more or less expelled prematurely before being compressed and fired. It is therefore the object of my invention to so improve upon the construction of two-cycle engines as to render them highly efficient and capable of developing an unusually high speed whether they be constructed with fixed or rotating cylinders.

With the foregoing general object in view, the invention resides in certain novel features of construction and unique combinations of parts to be hereinafter fully described and claimed, the descriptive matter being supplemented by the accompanying drawings which constitute a part of this application and in which:

Figure 1 is a vertical section through the several cylinders of an engine constructed in accordance with my invention;

Fig. 2 is an additional vertical section on the plane of the line 2—2 of Fig. 1;

Fig. 3 is a vertical section on the plane designated by the line 3—3 of Fig. 2;

Fig. 4 is a side elevation of one of the

fixed abutments which operate in conjunction with the hollow piston; and

Figs. 5, 6 and 7 are detail transverse sections through one cylinder on the planes of the lines 5—5, 6—6 and 7—7 of Fig. 1.

In the drawings above briefly described, the numeral 1 has reference to a crank shaft held against rotation in any suitable manner, the ends of said shaft being shown as provided with plates 2 rigidly secured thereto and carried by the inner ends of radially disposed supporting arms 3 which are preferably anchored at their outer ends to a circular guard 4 within which the engine cylinders rotate. The shaft 1 is provided with a main crank 5 extending in one direction and a pair of auxiliary cranks 6 extending approximately in the opposite direction and the usual port 7 is formed through a portion of said shaft for admitting an explosive mixture from the carbureter 8 into the crank case 9 which is rotatably supported on the shaft 1 between the main and auxiliary cranks.

A plurality of cylinders 10 radiate from the crank case 9 and communicate therewith, each cylinder having therein an inner piston 11 and an outer piston 12, both of which are hollow with open ends disposed toward the ends of the cylinder. A master connecting rod 13 extends into the crank case from one of the pistons 11 and carries a master bearing 14 on its inner end which is mounted on the main crank 5 of the shaft 1. The connecting rods 13^a of the other pistons 11 are pivoted to the master bearing 14 in the usual manner.

The outer pistons 12 are carried by shafts 15 which extend therethrough and through longitudinal slots 16 in the outer ends of the cylinders 10, one of said shafts 15 being carried by a pair of master connecting rods 17 having master bearings 18 on their inner ends mounted on the auxiliary cranks 6 of the shaft 1. The other shafts 15 are carried by connecting rods 17^a which are pivoted to the master bearings 18. This arrangement causes the inner and outer pistons to move toward and away from each other in unison.

Abutments 19 are disposed in the inner and outer pistons 11 and 12 and coöperate therewith in forming air and gas pumps which respectively scavenge the cylinders of burnt gases and fill them with an explosive

charge at proper intervals. Each abutment 19 is provided with a pair of comparatively resilient legs 20 normally spaced a greater distance at their free ends than the internal 5 diameter of the cylinders, whereby said legs when forced toward each other will be placed under tension so that laterally extending feet 21 on the free ends of said legs will be effectively held in sockets 22 formed on the 10 interior of the cylinders. This construction readily holds the abutments 19 in operative position yet permits them to be easily removed when required.

The outer ends of the pistons 12 have 15 formed therein air inlet ports 23 of a width greater than the thickness of the abutments 19 so that as said pistons recede from their respective abutments, a partial vacuum will be created which will be immediately filled 20 with air when the ports 23 reach the position shown at the lower end of Fig. 1. As the pistons 12 now move toward the abutments 19 the trapped air will be compressed and at the proper time ports 24 in the inner 25 ends of said pistons will permit this air to discharge into by-passes 25 which lead into the cylinders 10, this inrush of air being adapted to drive the exhaust gases from the cylinders through the exhaust ports 26 which 30 are uncovered by the pistons 12 (see the upper end of Fig. 1).

The inner ends of the inner pistons 11 are formed with ports 27 which establish communication between the interior of said 35 pistons and the crank case 9 when the former have receded a predetermined amount from their respective abutments 19 (see the lower end of Fig. 1). When the ports 27 of any piston are opened in this manner, explosive 40 mixture is drawn from the crank case into said piston and as said piston then moves toward its abutment as indicated at the left of Fig. 1, this mixture will be compressed. Then, at the proper time, a port 28 at the 45 outer end of piston 11 registers with a short by-pass 29 so as to permit the compressed mixture to be forced into the cylinder (see the upper end of Fig. 1). This injection of explosive mixture takes place immediately 50 after the air from the outer piston 12 has been forced into the cylinder to scavenge the same of burnt gases so that as the cylinders continue to rotate the two pistons move toward each other to compress the 55 charge which is fired at the proper time by any suitable ignition mechanism, spark plugs 30 being shown in the present embodiment of the invention.

In order to more clearly describe the operation of the engine, we will assume that the 60 four cylinders shown in Fig. 1 illustrate four positions of one cylinder during one revolution. At approximately position A the charge is fired in the cylinder between the two pistons 11 and 12 which have in the

mean time filled respectively with gas and air. The force of this explosion moves the cylinder toward position B, in which position, however, the force of the expanding gases is not exhausted, this force acting 70 not only to rotate the entire set of cylinders but to compress the gas and air trapped respectively in the pistons 11 and 12. Just before the position C is reached the outer piston uncovers the exhaust ports 26, allowing 75 the gases to escape and a little later but still before position C is reached the port 24 has registered with the by-pass 25 and the compressed air from piston 12 has been discharged into the cylinder to force 80 the burnt gases from the exhaust ports 26 and the port 28 has registered with the by-pass 29, thus conducting the compressed gas from piston 11 into the cylinder. As the cylinder now moves toward position D the 85 pistons 11 and 12 travel toward each other, close all ports and compress the new charge of mixture in readiness for firing at position A. As the cylinder moves from C to- 90 ward A the pistons 11 and 12 recede from their respective abutments 19 so as to create a partial vacuum and the moment this vacuum is relieved by opening of the ports 23 and 27, the two pistons again fill respec- 95 tively with gas and air.

The improved engine operating in the manner above described will develop not only great horse power but unusually high speed without loss of gas, and due to the pump actions at both the inner and outer 100 ends of the cylinders, the latter are maintained at an extremely low temperature. These pumps also serve as cushions to prevent loose vibration of the pistons and therefore cause the engine to run smoothly re- 105 gardless of the high speed at which it operates. Furthermore, since all pistons are hollow, and are extremely light and rotate around a common center, the centrifugal force acting thereon is balanced and reduced 110 to a minimum. A further advantage is that the improved arrangement of pistons allows a great expansion of gases with short piston travel and the pistons traveling in opposite directions will not receive such forcible 115 shocks from the explosion as in the ordinary engine in which one piston moves toward and from a fixed cylinder head. The pistons may therefore be made lighter and the ports will remain open a longer time at the 120 same speed than in the usual types of two- cycle engines.

The improved engine may be employed wherever applicable and power may be taken therefrom in any suitable manner, a 125 sprocket wheel 31 being shown in Fig. 2, for illustrative purposes, said wheel being secured to one of a pair of casings 32 which are carried by the crank case 9 and surround the auxiliary cranks 6 of the shaft 1. 130

- Particular emphasis is laid upon the fact that pumps are provided at the inner and outer ends of the cylinders on account of the advantages above pointed out and upon 5 the unique construction of the abutments whereby they may be quickly and easily attached or detached whenever necessary. The general construction shown is comparatively simple yet highly efficient and for these reasons constitutes the preferred embodiment 10 of the improved engine but it is to be understood that within the scope of the invention as claimed, numerous changes may be made without sacrificing the principal advantages.
- 15 I claim:
1. An internal combustion engine comprising a cylinder, a pair of hollow pistons in said cylinder having open ends disposed toward the ends thereof, fixed abutments disposed in said pistons, resilient legs extending from said abutments and having their free ends sprung into sockets in the cylinder, means for admitting air into one piston as it recedes from its abutment and for directing said air into the cylinder as said piston moves toward said abutment, whereby to scavenge the cylinder of burnt gases, means for admitting an explosive mixture into the other piston as it recedes from its abutment 20 and for directing this mixture into the cylinder as said last named piston travels toward its abutment, and means connecting said pistons for causing them to move inwardly and outwardly in unison.
  2. An internal combustion engine comprising a cylinder, a pair of hollow pistons in said cylinder having open ends disposed toward the ends thereof, fixed abutments disposed in said pistons, resilient legs extending from said abutments and having laterally extending feet at their free ends sprung into sockets in the cylinder, means for admitting air into one piston as it recedes from its abutment and for directing said air into the cylinder as said piston moves toward said abutment whereby to scavenge the cylinder of burnt gases, means for admitting an explosive mixture into the other piston as it recedes from its abutment and for directing this mixture into the cylinder as said last named piston travels toward its abutment, and means connecting said pistons for causing them to move inwardly and outwardly in unison.
  3. An internal combustion engine having a hollow piston open at one end, an abutment in said piston and forming therewith a gas or air pump, and resilient legs extending from said abutment and having their free ends sprung into internal sockets in the cylinder.
  4. An internal combustion engine having a hollow piston open at one end, an abutment in said piston and forming therewith a gas or air pump, and resilient legs extending from said abutment and having laterally extending feet at their free ends sprung into internal sockets in the cylinder.
  5. An abutment for use in a hollow piston of a gas engine to form therewith a pump, said abutment comprising a circular head, and a plurality of resilient legs extending from one side of said head for engagement with the engine cylinder to secure said abutment in place.
  6. An abutment for use in a hollow piston of a gas engine to form therewith a pump, said abutment comprising a circular head, a plurality of resilient legs extending from one side of said head, and laterally extending feet on the free ends of said legs for engagement with the engine cylinder to hold the abutment in place.
  7. An engine comprising a cylinder, a hollow piston therein, and a relatively fixed abutment in said piston forming therewith an air or gas pump, said piston having an inlet port of dimensions to form a by-pass around said abutment and having an outlet port for delivering into the cylinder.
  8. In a rotating cylinder engine, the combination of a fixed crank shaft, a crank case rotatable thereon and carrying a plurality of radially disposed cylinders in communication with said case, hollow pistons in the inner and outer ends of said cylinders and opening toward the ends thereof, relatively fixed abutments in said pistons, said pistons having inlet ports in their curved sides of dimensions to form by-passes around the abutments for admitting air and gas respectively into the outer and inner pistons, and also having outlet ports for discharging said air and gas into the cylinder to respectively scavenge and recharge the same, and means operatively connecting said pistons and the crank shaft for moving said pistons inwardly and outwardly in unison.
- In testimony whereof I have hereunto set my hand in the presence of two subscribing witnesses,

HARVEY J. WARNER.
